DESIGN FOR A COMBINED HAND AND DESK MICROPHONE

Robert L. Stone, Guilford, and Frank E. Runge,
Branford, Conn.

Application September 6, 1946, Serial No. 133,096

Term of patent 14 years

(Cl. D26—14)

To all whom it may concern:

Be it known that we, Robert L. Stone and Frank E. Runge, citizens of the United States of America; residing in the towns of Guilford and Branford, respectively, in the county of New Haven and State of Connecticut, have invented a new, original, and ornamental Design for Combined Hand and Desk Microphone, of which the following is a specification, reference being had to the accompanying drawing, forming part thereof.

Fig. 1 is a top plan view of the combined hand and desk microphone showing our new design.

Fig. 2 is a side view of the same.

Fig. 3 is a bottom plan view of the same.

Fig. 4 is a front view of the same.

The dotted line representation of a cable in

Figs. 1 and 2 is shown for illustrative purposes only.

We claim:

The ornamental design for a combined hand and desk microphone, as shown and described.

ROBERT L. STONE.
